Attorney.

UNITED STATES PATENT OFFICE.

SPRAGUE F. HASKELL, OF ST. LOUIS, MISSOURI, ASSIGNOR OF ONE-HALF TO CHARLES D. LYON, OF ST. LOUIS, MISSOURI.

WEATHER STRIP.

Application filed March 27, 1918. Serial No. 224,991.

To all whom it may concern:

Be it known that I, SPRAGUE F. HASKELL, a citizen of the United States, residing at the city of St. Louis and State of Missouri, have invented certain new and useful Improvements in Weather Strips, of which the following is a specification.

My invention relates to certain new and novel improvements in weather-strips for doors and other like closures and is a distinct and practical improvement to overcome certain important practical objections to, and defects in, the weather-strips disclosed in my former United States Letters Patent No. 926,409, dated June 29, 1909 and my United States Letters Patent No. 971,374 dated September 27, 1910, and has for its objects first, to provide an improved type of threshold tread plate having preferably an arched contact surface and adapted to be superimposed on the wood threshold for doors and be suitably fixed thereto, to provide a positive weather-proof joint therebetween; second, to provide by means of said improved type of threshold tread plate an effective outside water drip; third, to provide the door bottom with a resilient preferably concealed and protected weather-strip capable of yielding as the door is closed by coming progressively in contact with the said arched surface of the threshold tread plate to provide a positive weather-proof contact joint the entire length of the threshold tread plate between the threshold tread plate and the resilient weather-strip carried by the door; and, fourth, to provide at each end of the resilient weather-strip carried by the door, a resilient end contact means or ears to form a corner contact member for establishing continuous engagement in the closed position of the door between the said threshold tread plate, said resilient weather-strip and the usual flexible angle side weather-strips carried vertically by the door jambs. All the several elements being so designed and arranged as to provide or form a continuous line of weather-proof contact between the threshold tread plate, the resilient weather strip, the resilient end contact means and the flexible angle side weather-strips carried on the door jambs.

With the above and further objects in view, the invention consists in certain new and novel features of construction, arrangement and combination of parts, described in

the following specification and finally pointed out in the claims hereto appended.

Referring to the accompanying drawings forming a part of this specification wherein like characters of reference denote similar parts throughout the several views:

Fig. 1, is a view in perspective of a threshold, a portion of a door, partly broken away and provided with my improved threshold tread plate and resilient weather-strip and resilient end contact means or ears adapted for engagement with the usual flexible angle side weather-strips carried vertically by the door jambs.

Fig. 2, is a detail in perspective of a threshold tread plate made in accordance with my invention.

Fig. 3, is a detail in perspective of a portion of the tread plate and my improved resilient weather-strip carried by the door bottom showing same in its open position before being depressed into weather proof engagement with the arched portion of the tread plate.

Fig. 4, is a detail showing the lower cut away portion of the usual flexible angle side strips to accommodate itself for movement with relation to the arched portion of the tread plate.

Fig. 5, is a plan view of the threshold and tread plate arranged below a door as shown in section which is provided with my improved resilient weather-strip and resilient end contact means or ears, the latter being shown in engagement with the usual flexible angle side weather-strips fixed to and carried vertically by the door jambs.

Fig. 6, is a view in perspective of my improved resilient and depressible weather-strip adapted to be carried on the door bottom and showing the resilient end contact means or ears in relation thereto.

Fig. 7, is a front elevation of one of the resilient end contact means or ears.

Fig. 8, is a bottom plan view thereof.

Fig. 9, is an end elevation of the pocket forming plate.

Fig. 10, is a front elevation thereof.

Fig. 11, is an enlarged detail showing one end of a door carrying in closed position the resilient end contact means or ears in contact with the usual flexible angle side weather strip carried vertically by the door jamb.

Referring to the accompanying drawings

the reference character 1 designates the usual design of wood threshold, carpet strip or door sill; 2 the door in closed position between the jamb 3 and the lock edge jamb 4 and against outside stops 5 and 6, as shown in Figures 1 and 5.

In carrying out the aim of my invention I employ a suitable superimposed threshold tread plate 7 having an arched contact surface 8 terminating in such means as to form along its outer edge a water-drip 9. The arched portion 8 of the tread plate 7 is preferably supported by means of a suitable wood strip 10 seated upon and suitably fixed 10 to the wood threshold 1. The tread plate 7 preferably is provided with fluted supports such as 11 and 12 in addition to wood support 10 to separate and hold in position a suitable plastic adhesive weather-proof compound 13 adapted to be interposed between the wood threshold 1 and the superimposed tread plate 7 to provide a weather-proof joint therebetween, all as clearly shown in Fig. 1. The threshold tread plate 7 may be 20 secured in position upon the wood threshold 1 by any suitable fastening means, such as 14.

The bottom of the door 2 is preferably provided with a suitable recess 15 and 30 suitably protected upon one side with an outside plate 16, in mechanical economy of door treatment.

A resilient pendent weather-strip 17 is adapted to be carried by, and suitably fixed 35 to the bottom of door 2 and preferably concealed in the recess 15 behind the outer plate 16, as clearly shown in Figure 1.

The resilient pendent weather-strip 17, as shown in Figure 3, is so formed as to 40 provide a resilient under fold 18 with a looped edge 19 terminating in a forward, downwardly projecting and suitably curved resilient contact lip 20. The contact lip 20, when normally pendent is adapted to contact with, and over-ride into positive engagement with the arched surface 8 of the threshold tread plate 7, in the closed position 45 of the door, and to provide a weather-proof contact between the resilient contact lip 20 and the arched surface 8 of the threshold tread plate 7, thereby performing a blocked 50 line in weather proofing for the benefit of water drip 9.

The resilient contact lip 20 is provided at 55 each end with a suitably formed resilient end contact means or ear 21, preferably, in the form of vertically disposed ears capable of up and down movement with the resilient contact lip 20.

60 The inner face of each end contact means or ear 21 is adapted to engage and ride upon the outer face 22 of a suitable surface plate 23 fixed to each jamb edge of the door. The upper edge 24 of the end contact means or 65 ears 21 is adapted, when the door is closed,

to engage the stop shoulder 25 of the surface plate 23 and the extreme outer face 26 of said plate is adapted to be in a plane with the outer face of the resilient end contact means or ears 21, to provide an unbroken 70 plane for contact with the side weather-strip 27 adapted to be carried vertically on jambs 3 and 4 to complete the continuous weather-proof contact on each jamb edge of the door adjacent the stop corners thereof and, thereby, establishing the continuous weather-proof contact line, as shown by line A—A, in Figures 1 and 5, between the threshold tread plate 7, and the resilient contact lip 20 of the weather-strip 17 and between the ears 21 and the usual flexible side weather-strip 27 carried vertically by the door jambs 3 and 4.

A suitable cover plate 28 is superimposed on surface plate 23 and suitably fixed to the door to form a pocket recess 29 extending outwardly from the surface plate 23 and adapted for the reception and retaining of a portion of the resilient end contact means or ears 21.

The flexible angle side weather-strip 27 carried vertically by each door jambs 3 and 4, as shown in detail in Figure 4, is suitably cut away at the bottom edge, as at 30 to conform to the arched surface 8, of the threshold tread plate 7, to accommodate itself for movement with respect thereto when in contact with and depressed by both jamb edges of the door on continuous weather-proof contact line A—A in a closed 100 position of the door.

From the foregoing description it will be readily observed that I have so formed and assembled an improved weather-strip for doors as to provide a continuous line of 105 weather-proof contact on all sides of the door when in a closed position and the many advantages thereof will readily suggest themselves to those skilled in the art to which the invention appertains.

While, for convenience, I have illustrated and described but one form of my invention, I wish it to be understood that I am well aware that the exact details of construction of the several parts illustrated in the drawings and herein described are not essential to the invention, and being aware that minor changes in the form and proportions of the several parts may be made without departing from the spirit of my invention, I reserve 115 the right to make any such changes or modifications as may fairly fall within the scope of the appended claims when fairly construed.

What I claim is:

1. A weather strip comprising a section terminating along one edge in a resilient underfold section having a looped edge which terminates in a forward downwardly projecting and suitably curved resilient 130

contact lip section capable of yielding upwardly when the lower face of the curved portion of the lip is brought into frictional contact with an adjacent member and an upwardly projecting ear fixed to each end of the resilient contact lip section for movement therewith.

2. In a door structure, provided with a swinging door, weather stripping comprising flexible metal side strips secured to the door frame, a fixed tread plate mounted upon the door sill and provided with an arched contact surface and a metal weather strip comprising a section fixed to the lower edge of a door and secured in a recess in the lower edge of the door, said section terminating along one edge in a resilient underfold running parallel therewith and having a looped edge which terminates in a forward,

downwardly projecting and suitably curved resilient lip section for frictional contact with the arched surface of the tread plate and an upwardly projecting ear fixed to each end of the resilient lip section for up and down movement with the resilient lip section and for contact with the metal side strips secured to the door frame, said lip section and ears being adapted to establish a continuous line of weather proof contact with the metal side strips carried by the door frame and with the arched surface of the tread plate to seal any crevices between the bottom of the door, the sill and lower portions of the frame.

In testimony whereof, I have hereunto signed my name to the specification.

SPRAGUE F. HASKELL.
